UNITED STATES PATENT OFFICE.

WILLIAM F. DAKE, OF GRAND HAVEN, MICHIGAN, ASSIGNOR OF TWO-THIRDS
TO HIRAM P. PRUIM AND THOMAS CAIRNS, BOTH OF SAME PLACE.

DOUBLE RECIPROCATING SQUARE-PISTON ENGINE.

SPECIFICATION forming part of Letters Patent No. 363,368, dated May 24, 1887.

Application filed December 11, 1886. Serial No. 221,341. (No model.)

To all whom it may concern:

Be it known that I, WILLIAM F. DAKE, a citizen of the United States, residing at the city of Grand Haven, in the county of Ottawa 5 and State of Michigan, have invented certain new and useful Improvements in Steam-Engines, of which the following is a specification.

My invention relates to that class of engines having two rectangular pistons adapted to work in a case, said pistons acting together conjointly for the purpose of producing a revolution of the main shaft, the construction being such that the pistons themselves act as valves in operating the engine, as illustrated 15 in the accompanying drawings, in which—

Figure 1 is a front elevation of an engine constructed in accordance with my invention. Fig. 2 is a sectional view on line $y-y$ of Fig. 3. Fig. 3 is a sectional view on line $X-X$ of Fig. 20 1. Fig. 4 is an inside view of the face-plate, the outside view of which plate is shown in Fig. 1. Fig. 5 is a perspective of the inner piston upon an enlarged scale, in order to show more fully its construction and operation.

25 Similar letters refer to similar parts throughout the several views.

A A represent the surrounding case, which may be made of iron, steel, or any suitable material.

30 B B' is a rectangular piston situated within the outer case, A A, and in close contact with the upper and lower inner faces of the surrounding case, and adapted to move horizontally backward and forward within the case.

35 C C' is the inner piston, which has a reciprocating motion vertically within the outer piston, B B'.

D D represent the face-plate.

E is the shaft of the engine, provided with 40 the crank F, which crank F engages with the inner piston by means of the wrist-pin T, the end of which is shown in Fig. 5.

G is a packing-plate between the pistons and the back of the frame or case, which is so constructed as to be adjustable to take up any wear which may be caused by the movement of the pistons within the case, and which thereby prevents leakage of steam. A similar packing-plate may be used between the front 45 50 of the case and the front of the pistons, if desired.

H is a lever which may be used for operating the four-way valve, which is one of the ways of reversing my engine. Other well-known devices may be used for this purpose, 55 if desired.

I is a valve operated by the lever H.

K and K' are steam passage-ways connecting with the steam passage-ways M and M' and conveying the steam alternately in reversing the engine, as more fully described hereinafter. The passage-ways M and M' conduct the steam to the passage-ways K and K'.

The outer piston, B B', moves in the chamber N N', formed by the inclosing-case A A, 65 while the inner piston, C C', moves in the chamber O within the outer piston. I prefer to make the inner piston with two parts, as shown in Fig. 5, for convenience in arranging the steam-passages. The faces of the inner piston serve the purpose of valves.

R and R' are steam-ports opening from the piston C C' into the chamber N N'. S and S' are also ports opening from the inner piston into said chamber N N', all arranged as shown 75 in the drawings.

U and U' are openings from the steam-passages K and K', arranged upon the front plate and so constructed as to convey the steam at proper times into the inner piston. The steam-passages K and K' are located upon or within the face-plate D and cross each other, as shown in the drawings. The outer piston, B, fits within the frame, so as to form a steam-tight packing; or it may be provided with suitable 85 packing, if desired. The valve faces of the inner piston also fit closely within the sides of the outer piston, so as to be steam-tight. Any ordinary steam-packing may be used in connection with this piston.

c is a steam-passage through the upper face of the outer piston, and f f' and f' f' are steam-passages connecting with the ends of the steam-passages K and K' and cut into the inner surfaces of the top and bottom of the case A A, 95 each passage f f' extending from the point of connection with K K' far enough back to permit connection with the ports c and d as the outer piston moves back and forth horizontally.

d is a steam-passage through the outer piston, so arranged as to conduct the steam alter-

nately to or from the lower ends of the steam-passages f and f' .

a and b are ports through the sides of the outer piston leading into the chamber N N' .

5 The operation of my invention is as follows: I admit the steam through the valve I into the steam-passage M' , filling the steam-passages f' and chamber C' by means of the passages K' and the openings U . The steam escapes 10 through the passage-way S into the chamber N through the port a , thus forcing the outer piston, B B' , to the left until the port c connects with the chamber f' , taking steam from above into the piston B B' , forcing the inner piston down, which, as it descends, cuts off S 15 and connects ports R and b . The steam now passes from C' into the chamber N' , forcing the piston B B' to the right, and the port d connects with the lower passage-way, f' , taking the steam into the chamber O below the 20 inner piston, forcing it upward, thus completing the circuit. When the valve I is in the position shown, the exhaust-pipe e is connected with the passage M , which passage connects with the chambers ff and C by means of the passage K and opening U' . While the 25 live steam is entering, as above described, through the various passages at one side of the piston the exhaust-steam is escaping from the opposite side of the said piston through the corresponding ports connecting with these 30 described chambers and passages. Upon reversing the engine the live steam passes through the opposite passages and chambers, 35 and thereby causes the pistons to travel in the opposite direction, revolving the shaft in the opposite direction.

It will be observed that by the construction 40 of this engine there are no valves whatever, excepting the faces of the pistons, and no eccentric or other device is needed to operate

the valves, the action being directly upon the pistons, and the pistons themselves acting as valves to cut off and let on steam at the proper time to give the continuous motion to the engine. By this construction the engine is very compact and light and effective, and possesses great power for the space occupied by it. 45

Having thus described my invention, what I claim to have invented, and desire to secure by Letters Patent, is—

1. In a double-acting square-piston engine, the combination of an outer shell adapted to inclose two pistons, a piston adapted to have a reciprocating motion within the shell, and an inner piston having a reciprocating motion within the outer piston, said piston moving at right angles to the motion of the outer piston, and said pistons serving as valves, substantially as described. 55

2. In a double-acting reciprocating engine of the class described, the steam-passages K and K' and the pistons having steam-ports a and b c and d , steam-passages S and S' , and ports R and R' , in combination with the surrounding case, substantially as described. 65

3. The inner piston having the valve-faces described and ports R R' and S S' , in combination with the outer piston and surrounding case, substantially as described. 70

4. In a steam-engine of the class described, an inner piston in combination with an outer piston, said inner piston having two steam-chambers separated from each other, and also having ports through which the steam is conducted into the chamber in which the outer piston moves, substantially as described. 75

WILLIAM F. DAKE.
